DISPENSING CONTAINERS

Donald Waber and Raymond Braunstein, Jr.,
Philadelphia, Pa.

Application January 5, 1952, Serial No. 265,147

2 Claims. (Cl. 221—246)

Our invention relates to new and useful dispensing containers and has for one of its objects to incorporate an individual dispensing mechanism in a receptacle whereby a restricted outlet opening is provided for dispensing articles, one at a time, from the underneath portion of the receptacle so that only the one article which is being dispensed has a chance of being exposed to outside detrimental effects.

Another object of our invention is to utilize some of the principles embodied in the type of dispensers disclosed in U. S. Patents Nos. 1,958,101 and 1,962,860 as well as those shown in our copending application Ser. No. 235,502, filed July 6, 1951, which has issued as Patent No. 2,605,892, August 5, 1952, and combine with conventional elements thereof certain new elements to provide a novel structure which will accomplish the dispensing operation in an unusual manner.

Another object of this invention is to produce a dispensing container which is simple in construction although highly efficient in operation for propelling successively a predetermined number of the contained articles through an outlet and delivering the same without the necessity of inverting the container.

Another object of the present invention is to produce a dispensing container of the portable type and especially one which can be held in and operated by one hand of the user particularly by oscillations of the thumb.

Another object of our invention is to produce a dispensing container especially adapted for use in delivering small tablets from the container or receptacle through an outlet located midway between the sides and including a relatively small sliding panel on the fixed top wall or lid of the container and said panel supporting a closure and ejector so related as to first cause a predetermined number of tablets to be isolated or separated from the main compartment of the container and the articles therein and subsequently cause the outlet to be opened and the isolated or separated tablets to be ejected due to an outward movement of the sliding panel, said ejector also functioning as a barrier while the outlet is open to prevent unwanted discharge of other tablets during the dispensing operation.

Another object of this invention is to provide unique means for mounting the sliding panel on the container top, closing any apertures utilized as a part of the mounting, and limiting the reciprocating movements of said sliding panel.

A further object of the invention is to divide the interior of the container into a main or holding compartment of appreciable depth and a shallow delivery compartment, said compartments being in communication through a gradually decreasing passageway formed by an inclined wall or ramp between the bottoms of said compartments.

A still further object of the present invention is to produce a normally completely closed dispensing container having the interior divided into holding and deliv-

2

ery compartments, the bottom of the delivery compartment being in a relatively higher offset plane than the bottom of the holding chamber when the container is level, the depth of the delivery compartment or 5 the space between the bottom of the latter and the container top being less than one of the dimensions of the tablets to be dispensed but substantially the same as the other dimensions of said tablets whereby the tablets can enter the delivery compartment in only one position, 10 and an inclined wall or ramp joining the adjacent ends of the bottoms of said compartments.

With the above and other objects in view this invention consists of the details of construction and combination of elements hereinafter set forth and then designated 15 by the claims.

In order that those skilled in the art to which this invention appertains may understand how to make and use the same we will describe its construction in detail referring by numerals to the accompanying drawing 20 forming a part hereof, in which:

Fig. 1 is a top plan view of the dispensing container constructed in accordance with the present invention.

Fig. 2 is a section on the line 2—2 of Fig. 1 in a tilted position for causing the articles in the container, herein 25 shown as small tablets, to travel towards and into the delivery compartment.

Fig. 3 is a similar view showing the position of the sliding panel, with the associated closure and ejector, during a dispensing operation.

30 Fig. 4 is a section on the line 4—4 of Fig. 2 illustrating certain details of construction and showing the position of the closure and ejector when the container is completely closed.

Fig. 5 is a cross section of the apparatus on the line 35 5—5 of Fig. 1.

Fig. 6 is a perspective view of the sliding panel looking at the bottom or underneath face thereof.

Fig. 7 is an enlarged detail section of the sliding panel on the line 7—7 of Fig. 6.

40 Fig. 8 is a fragmentary perspective view of the lid or cover looking at the front end thereof.

Fig. 9 is an enlarged fragmentary section of the container illustrating a means for attaching the lid or cover to the body.

45 Fig. 10 is a similar view through the container body and sliding panel to illustrate a means for temporarily retaining the sliding panel in a retracted position and the closure in a closed condition.

In carrying out our invention as herein embodied 50 and 16 represent, respectively, a container or receptacle body and a lid or top formed from any suitable material having sufficient stiffness or rigidity to retain the shapes desired and also having some inherent resiliency for purposes to be later fully described. Either or both the body and lid may be opaque, translucent or transparent.

The device is particularly adapted for dispensing small articles, such as tablets, and especially tablets of the type comprised of saccharine, wherefore it is desirable that the container be relatively thin, of laterally elongate 60 transverse configuration throughout its entire length and probably of generally rectangular overall shape such as oblong. The body comprises a bottom having two different levels including the base portion 17 at a low level and a platform 18 at a higher level considered with the container in a horizontal position. Preferably the platform 18 is of less area, particularly lengthwise of the container, than the base 17 and said platform and base are joined by an incline or ramp 19 leading from the

65 forward end of said base to the rear of said platform. From the bottom project the upwardly extending perpendicular rear wall 20, opposite side walls 21 and the 70

angular front walls 22, 23 which extend outwardly from their respective side walls in convergent formation to provide what will be termed a laterally tapering spout for purposes of description.

Each of the angular front walls 22, 23 is of bi-angular formation including a long oblique portion 24, contiguous a side wall forming an obtuse angle to the longitudinal axis of the body, and a relatively short oblique portion 25, extending from the outer end of the oblique portion 24 and forming an acute angle to said axis of the body. The short oblique portions of the front walls are spaced apart an appropriate distance to form the restricted outlet 26. The longer oblique portion 24 of the front wall 22 is thickened to provide a projection 27a on the inside thereof for guiding articles over the end of the ejector to be presently described.

The lid, top or cover 16 is substantially permanently secured to the body, more particularly to the rear, side and front walls thereof, and for purposes of illustration only, this lid is shown as recessed into the body walls and provided with sockets 27, Figs. 5, 8 and 9, to receive projections 28 on the body walls. The inherent resiliency of said body walls permits the lid to be forced into place and then, for all intents and purposes, permanently held in position. This lid is of the same configuration as the body in plan and provides a completely enclosed container except for the outlet opening which is controlled by a closure.

When the lid 16 is in place a relatively deep end region or holding compartment 29 of appreciable depth is provided at the rear of the container between said lid and the base 17 while a shallower end region or delivery compartment 30 is provided at the forward end of the container between said lid and the platform 18. The intermediate receptacle region adjacent to the ramp 19 communicates between the holding and delivery compartments 29 and 30 and is of gradually decreasing depth from the former compartment to the latter compartment. Articles 31, here represented as tablets having greater diameters than thickness, can be placed in the holding compartment at random and when the lid is assembled on the container said articles will not be crushed. When the container is tilted with the forward end down and given a slight shaking the tablets will be thrown onto their flat sides so that they may enter the delivery compartment 30 which will only receive such tablets that are lying flat. That is, the delivery compartment is of a depth greater than the thickness and less than the diameter of a pill or tablet. Any tablets that are on edge are too large to enter the delivery compartment and will remain in the holding compartment 29 or on the ramp 19 from which they may roll back into said holding compartment.

In the restricted or tapered end of the lid is formed a longitudinal open ended elongated aperture 31 in the longitudinal axis of said lid and the edges of the walls surrounding said aperture are reduced in thickness to form portions 32 of a lap joint or tracks for the sliding panel. To the rear of and spaced from said aperture is a longitudinal slot 33 to limit the movements of the sliding panel.

The sliding panel 34 is mounted to slide to and fro longitudinally and has a pendant rib 35 to fit the aperture 31 with flanges 36 projecting laterally from the lower or inner edge of said rib and spaced from the panel, parallel therewith, a distance equal to the thickness of tracks 32 so that when the parts are assembled the panel cannot be lifted out of place but can be slidingly reciprocated. The sliding movements of the panel, with its component parts, is limited by a pin 37 or equivalent means projected through the rear portion of said panel and registering with the slot 33. The rear end of the panel 34 is feathered or beveled at 38 and the corners of the container may be rounded to eliminate any sharp prominences.

At the forward end of the sliding panel 34 is a pendant closure 39 which normally closes the exit opening from the outlet 26 and said closure preferably snugly fits into said outlet whereby the outer face of said closure will be flush with the terminal edges of the angular front walls 22, 23, the bottom and lid or cover. Means is provided to temporarily retain the closure in a closed position and the associated parts retracted which means, for purposes of illustration, is shown as a rounded projection 40 on one coating part, as the closure 39, for registration with a socket or depression 41 in the other coating part, as the bottom wall of the container and more specifically the platform 18.

An ejector 42, which also functions as an agitator and a barrier, depends or hangs from the underside of the sliding panel, particularly the flange structure 36 of said panel, into close proximity to the platform portion of the container bottom wall. Said ejector extends rearwardly from the closure an appreciable distance longitudinally of the sliding panel so that when the closure is closed the rear end of said ejector projects into the delivery compartment but when said closure is in the fully open position the rear end of the ejector will be within the outlet 26.

The ejector includes a relatively thin stem 43 perpendicular to the sliding panel and a lateral nib 44 at the inner or rear end of said stem. The nib has a substantially flat forward face, for engaging an article to propel the latter forwardly, and a curvilinear side face to deflect other articles within the delivery compartment of the container.

This ejector 42 is positioned to one side of the sliding panel so that said ejector assumes a position to one side of the outlet 26 with the back of the ejector close to the acutely oblique portion 25 of the angular front wall and with the nib projecting towards the opposed portion 25 of the other angular front wall 23. The nose of the nib, formed by the meeting of the flat forward face with the curvilinear side face, is spaced from the adjacent portion of said front wall 23, at approximately the location where the oblique portion 24 blends into the oblique portion 25, to provide an entrance to the outlet 26 while the ejector is retracted. This entrance is of sufficient width to allow for the passage of a single article into the outlet to assume a position forward of the flat pusher face of the ejector and beside the stem 43.

When the outlet 26 ahead of the ejector nib is filled additional articles cannot enter and as the ejector is projected forwardly for delivering the contents from said outlet 26 during the dispensing operation, the entrance to the outlet 26 is gradually decreased laterally to prevent other articles from accidentally passing out of the container. At the time the ejector reaches its fully projected position the rear end thereof will align with the inner surface of the projection 27a of the front wall 22 to cause articles at the back of said ejector to roll or slide over the latter to positions in front of the location of the ejector.

During retraction of the ejector, the inner or rear end thereof will function as an agitator by engaging any articles in the path of rearward travel and thereby scatter, to some extent, the articles in the delivery compartment 30 to assist in positioning them for subsequent entrance into the outlet and also loosening any jammed articles.

So that the closure and ejector may be readily operated to and fro by the pressure of a person's thumb a suitable area of the exterior surface of the sliding panel may be roughened in any well known manner, as by forming ridges thereon.

The operation of the device is as follows: A pre-selected number of articles are placed in the holding compartment 29, at random, and the lid or cover 16 fastened in place so as to be stationary and relatively permanent. The container is now held in one hand in a forwardly tilted position to cause some or all of the arti-

cles to travel over the ramp 19 and enter the delivery compartment 30. One or more of the articles, depending upon the relative dimensions of the device and the articles, will pass the nose of the ejector nib 44 and enter the outlet 26 ahead of the flat pusher face of said nib and rest against the closure 39. By proper motion of the thumb the sliding panel 34 will be projected forwardly carrying the closure and ejector with it. This action will open the outlet and the ejector will push any articles before it out of the outlet where they may drop onto a surface or the person's other hand, or directly into the person's mouth without the necessity of inverting the device. The sliding panel is then retracted by a reverse movement of the thumb and the ejector will push articles in its rearward path of travel to either side so as to ready them for travel towards the outlet and dislodge any that may have become jammed. Simultaneously the closure will be moved to the closed position and other articles may enter the outlet ready to be dispensed. If none of the articles enter the outlet, a slight movement or shake of the device will cause them to move into line for travel past the nose of the nib. The operations may be repeated as often as desired and at any intervals of time.

During the dispensing operations if any of the articles are turned so that their greater dimensions are substantially perpendicular to the bottom of the device they will be prevented from entering the delivery compartment 30 until they are tipped over to present the smaller dimension in an upright position. This can be accomplished by simply shaking the container until the articles fall over and thereafter such articles will enter the delivery compartment.

While we have illustrated the bottom of the container as having an offset portion to define the platform 17 from the base 18, it will be obvious that said bottom may be continuous in one plane and the platform produced within the interior of the container.

Of course we do not wish to be limited to the exact details of construction herein shown and described as these may be varied within the scope of the appended claims without departing from the spirit of our invention.

Having described our invention what we claim as new and useful is:

1. In a container for dispensing disc-like pills in predetermined limited quantities; a hollow receptacle of generally laterally elongate transverse cross section through-

out its entire length and including a relatively deep end region adapted to contain a considerable number of pills in random orientation, a relatively shallow end region remote from said relatively deep end region and of a depth greater than the thickness and less than the diameter of a pill so as to contain said pills in a coplanar orientation, and an intermediate receptacle region communicating between said end regions and of gradually decreasing depth from said relatively deep end region to said relatively shallow end region to guide said pills from said random orientation in said relatively deep end region to their coplanar orientation in said relatively shallow end region, said relatively shallow end region tapering laterally in the direction away from said intermediate region and terminating in a restricted outlet of sufficient size to pass only a predetermined quantity of pills, a closure mounted on said receptacle for reciprocation between a position closing said outlet and a position outwards of and opening said outlet, and an ejector inwards of said closure and rigidly connected to the latter for movement therewith toward and away from said outlet and spaced from said closure to receive said predetermined quantity of pills in the space between said closure and ejector, said ejector being spaced from one tapering wall of said relatively shallow region in the extreme position of ejector movement away from said outlet to individually admit said pills into the space between said ejector and closure and moveable toward said one tapering wall upon opening movement of said closure to prevent the admission of pills into the last mentioned space, whereby said ejector serves to deliver only said predetermined quantity of pills toward said outlet upon opening of said closure.

2. A container according to claim 1, said ejector including a nose projecting inwards into said relatively shallow end region and moveable with said ejector to agitate pills in said region.
